Assistant Examiner — Lillian Windham

CLAIM

The ornamental design for a spectrum analyzer, as shown and described.

DESCRIPTION

- ## 1. Spectrum analyzer

- ## 1.1 : Front

- 1.2 : Right

1.3 : Top
The broken lines, other than those indicated in the grid area, do not form part of the claimed design; the left view is omitted because it is a mirror image of the right view; the bottom view and the back view are omitted because they do not include any of the claimed areas.

1 Claim, 3 Drawing Sheets
